CLAIM

The ornamental design for a floating conductor for bipolar discharge-dissipation lightning air terminals, as shown and described.

DESCRIPTION

FIG. 1 is a front, top perspective view of a floating conductor for bipolar discharge-dissipation lightning air terminals showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof; and,

FIG. 8 is a cross-sectional view taken along line A—A of FIG. 2.
